Primary Examiner — Paula Greene(74) *Attorney, Agent, or Firm* — Michael G. Kelber; Neal, Gerber & Eisenberg LLP(57) **CLAIM**

The ornamental design for audio listening system, as shown and described.

DESCRIPTION

FIG. 1 is a perspective view of the audio listening system in accordance with the present invention;

FIG. 2 is a front view of the embodiment of the audio listening system depicted in FIG. 1;

FIG. 3 is a right side view of the embodiment of the audio listening system depicted in FIG. 1;

FIG. 4 is a left side view of the embodiment of the audio listening system depicted in FIG. 1;

FIG. 5 is a back view of the embodiment of the audio listening system depicted in FIG. 1;

FIG. 6 is a top view of the embodiment of the audio listening system depicted in FIG. 1; and,

FIG. 7 is a bottom view of the embodiment of the audio listening system depicted in FIG. 1.

The broken lines showing the environment in the figures are for illustrative purposes only and form no part of the claimed design.
